RADIANT TUBE HEATER

Arthur H. Vaughan, Salem, Ohio, assignor to The
Electric Furnace Company, Salem, Ohio, a cor-
poration of Ohio

Application January 6, 1939, Serial No. 249,605

21 Claims. (Cl. 126—91)

This invention relates generally to radiant tube heaters for furnaces and is an improvement over the radiant tube heater described in my Patent 2,146,410, granted February 7, 1939. Such heaters are especially adapted for heating industrial furnaces having a controlled atmosphere in which the relatively low cost of gaseous fuel is an advantage but in which the products of combustion of the fuel must be kept from contact with the work being heated.

Many attempts have been made heretofore to produce a radiant tube heater in which the liberation of heat from the radiant tube is substantially uniform throughout the effective length of the tube. These attempts have not proved altogether satisfactory. I have found that such uniformity of temperature distribution may be obtained by employing a secondary air pipe within the combustion tube and providing the secondary air pipe with air holes spaced along the air pipe in a manner which is more particularly pointed out hereinafter. The distribution of the air holes is not uniform along the air pipe but is in accordance with a graph or curve which I have found to produce substantially uniform heating throughout the effective length of the combustion tube. This will be referred to in detail later on. The non-uniform distribution of the air holes prevents the occurrence of local hot spots, and the invention also provides baffles adjacent the air holes for preventing direct impingement of the air on the combustion tube and creates turbulence of the fuel and air so as to aid in uniform and complete combustion.

In the accompanying drawings, which illustrate a preferred embodiment of my invention,

Fig. 1 is a fragmentary transverse vertical section of a furnace embodying my radiant tube heater;

Fig. 2 is a fragmentary longitudinal sectional view of a heater, the view being on a larger scale than Fig. 1;

Fig. 3 is a transverse vertical section through the heater taken on the line III—III of Fig. 2; and

Fig. 4 is a diagram showing correct and incorrect hole distribution in the secondary air pipe, together with the resulting temperature distribution obtained with each type of air hole distribution.

Referring now more particularly to the accompanying drawings, the radiant tube heater comprises a combustion tube 2 which, as shown, is straight and of uniform diameter throughout the

greater part of its length. The ends of the combustion tube extend through openings 3 and 4 in the side walls 5 and 5a of the furnace. The left hand end of the combustion tube, as viewed in Fig. 1, has a tapered portion 6 and a portion 7 of smaller diameter than the main portion of the tube, the portion 7 extending outwardly beyond the furnace wall. A sealing means 8 is provided for making a tight seal between the furnace wall and the extension 7 while allowing contraction and expansion of the combustion tube. A burner 9 extends into the left hand end of the combustion tube, the space between the burner and extension 7 being sealed by a cap 10. The burner is connected to a supply of fuel and air (not shown). The fuel control apparatus is preferably of the type referred to in my above mentioned application which maintains substantially constant the relative amounts of fuel, primary air and secondary air. The non-uniform spacing of the air holes in the air pipe as contemplated in the present invention is, however, independent of any particular type of fuel control, it being adapted for use with various types of controls.

The right hand end of the combustion tube extends through the opening 4 in the furnace wall and has a flange 11 welded to it as indicated by the reference numeral 12. This flange 30 may be bolted or otherwise secured to a flange 13 secured to the furnace wall so as to clamp sealing material 14 between the two flanges. The end of the combustion tube is provided with a chimney 15 for delivering the products of combustion.

A secondary air pipe 16 is located within the combustion tube. It extends through the right hand end of the combustion tube, that is the end of the combustion tube opposite to that at which the burner 9 is located. The secondary air pipe extends substantially throughout the effective length of the combustion tube and is provided at intervals along its length with series of air holes 17, these series of air holes being distributed non-uniformly, as will be described in detail later. A baffle 18 is located adjacent each of the series of air holes for preventing direct impingement of the secondary air on the combustion tube. These baffles are shown more in detail in Figs. 2 and 3. Each of the baffles consists of a hub 19 which is welded as indicated by the reference numeral 20 to the outside of the secondary air pipe 16, and wing portions 21. Some or all of the baffles may be provided with centering lugs 22 which fit loose-

ly in the combustion tube 2 and locate the air pipe approximately centrally therein.

The baffles are so located along the air pipe that the air stream issuing from each hole 17 strikes the inner surface of the wing portion 21. In this manner a blow pipe action upon the wall of the combustion tube 2 is prevented while the shielding effect of the radial portion 23 of the wing is sufficient to avoid destructive action upon the wing itself. The wings cause turbulent flow of the moving gases in the space between the air pipe and combustion tube which improves the mixing action and the transfer of heat to the combustion tube wall.

Any convenient number of wings may be formed upon a baffle but for radiant tubes of ordinary size, say up to 5" outside diameter, I prefer to use four. Where only two holes 17 are used at any point along the length of the secondary air tube, they are located diametrically opposite one another, the baffle wings with which no holes are associated functioning only to produce turbulence. In case there are two adjacent baffles each with only two air holes associated with them, I stagger the holes, so that the center line of the pair corresponding to one baffle is at right angles to adjacent pairs. Groups of four or more holes may likewise be staggered, though I have not found this necessary. Other forms of baffles may be used in place of the particular type described but they should be such as to protect the combustion tube from direct air jet impingement and to produce a desirable amount of turbulence.

The secondary air before issuing through the openings 17 is preheated by the waste products of combustion flowing out of the right hand end of the combustion tube. In Fig. 1, the secondary air is preheated in a preheater or recuperator 25 located intermediate an air supply pipe 26 and the secondary air pipe 16. The recuperator is of larger diameter than the secondary air pipe so as to cause the products of combustion to flow into intimate contact with its outer wall. Inside of the recuperator is a cylindrically shaped baffle 27 which causes the incoming secondary air to flow into intimate contact with the wall of the recuperator. A considerable degree of preheat is thus obtained, with appreciable reduction in the fuel requirements and the further advantage of greater ease in disposing of the cooler waste gases. I have found it entirely practicable to reduce the waste gas temperature to 1200° F. or lower when operating at a tube surface temperature of 1700° F. The heat corresponding to this reduction is obviously returned as useful heat to the interior of the tube.

In the preferred manner of operating the heater, the burner 9 delivers a fuel-rich mixture of gas and air to the interior of the combustion tube 2. This mixture generally contains from 50 to 65% of the air required for complete combustion. The additional air necessary for complete combustion is supplied through the secondary air pipe 16, the secondary air issuing from the openings 17 and mixing with the gases flowing through the space between the combustion tube and the secondary air pipe. There is thus an initial partial stage combustion in the zone A, followed by further and progressive combustion as the products of the initial combustion stage travel through the combustion tube. If the total amount of air supplied is correct and thorough mixing is effected, the combustible content is exhausted at or slightly before the plane of the

inner face of the wall 5a is reached. The result is the liberation of heat throughout the entire active length of the heater with far better uniformity of tube temperature than would result if a complete mixture of fuel and air were admitted through the burner.

I have found that the desired general heat distribution from end to end of the heater depends upon the admission of secondary air at the proper rate as the gases pass from inlet to outlet end of the heater and that this is by no means a uniform rate per unit of length in the usual forms where a uniform rate of heat output is desired. I have found also that if unshielded holes are employed in the secondary air pipe, the combustion tube is subjected to local overheating opposite these holes due to the blow pipe action of the issuing jets. Furthermore, the mixing of combustible gases and secondary air tends to be incomplete.

I shall now refer more particularly to the arrangement of air openings in the secondary air pipe required to produce uniform heating throughout the effective length of the combustion tube. These openings may be of various sizes and of other than round form but drilled holes of uniform size are usually preferable from both designing and manufacturing standpoints. Such holes will, therefore, be assumed for the purposes of this description. One would expect that a substantially uniform spacing of holes through the greater part of the length of the pipe 16 would produce a desirable uniformity of useful heat liberation. I have found, however, that such is not the case. The heat distribution is affected by a number of variables, including the following:

Varying temperature of secondary air discharged by orifices at different points in the air pipe length.

Amount of preheat obtained in the recuperator. Increasing velocity of flow of gases as the outlet end of the heater is approached.

Equilibria of partial combustion reactions as affected by operating temperature and other factors.

These variables are such as to render impracticable any theoretical calculations and I have found it necessary to determine the air hole spacing by empirical methods. Such methods are not burdensome since a generally similar spacing applies in most cases and if a heater is to be built of a new size or for new operating conditions not differing widely from previous experience, a spacing can be assumed which will require no more than minor changes after experimental operation.

Referring now more particularly to Fig. 4, at the top of the figure is shown a diagram of a radiant heater tube assembly, drawn to scale as regards dimensions in the direction of tube length. At the bottom (in solid lines) is shown diagrammatically the air hole distribution which is actually used with satisfactory results in one furnace built under my direction. Adjacent the solid-line diagram is plotted (in dot-and-dash lines) a uniform air hole distribution along the secondary air pipe which I have found to give unsatisfactory results. In the central part of the figure are shown tube temperature curves illustrating the type of temperature distribution (though not necessarily the exact values) resulting from both kinds of air hole distribution.

In the actual heater represented, a primary mixture of about 6½ parts air and one part of gas is introduced through the burner 9. The

composition of the gas is approximately as follows:

Methane, CH ₄	per cent.....	84.6
Ethane, C ₂ H ₆	do.....	13.4
Nitrogen, N ₂	do.....	2.0
Air/gas ratio for perfect combustion, approximately		10.3

Approximately 4.8 parts of secondary air are introduced through the secondary air pipe 16. The total represents 10% excess air over that required for perfect combustion. The initial stage of combustion occurs in the space, designated A, between the burner nozzle 9 and the first point of admission of secondary air, which is at the second baffle 18, and designated 18a. There are no air holes associated with the first baffle, which serves merely to center the pipe and to assist the combustion reaction by producing turbulence. At each of the second, third, fourth, fifth and sixth baffles two holes are located, and at each of the remaining ones there are four holes. All holes are $\frac{1}{4}$ " diameter. Progressive further combustion takes place following each stage of secondary air admission until the combustible content of the fuel has been exhausted.

In the lower part of Fig. 4, the horizontal axis or abscissa represents distances in inches measured from the inner face of the furnace wall 5 adjacent the fuel inlet. The vertical axis or ordinate represents the number of air holes (and also obviously the total air hole area) between the inner face of the furnace wall 5 and any given point on the air pipe. The solid zig zag line a shows the distribution of air holes actually used and corresponds to the air hole distribution shown in the upper part of Fig. 4. This line rises vertically at each hole location a distance representing the number of holes at that location. The crests of the zig zag line b have been connected by a series of straight lines approximating a smooth curve which is upwardly concave. Under these conditions, it will be obvious that the rate of secondary air admission to the combustion tube, per unit of length, increases as the waste gas outlet is approached.

In a similar manner, the dot-and-dash lines d and e represent a uniform hole distribution along the secondary air pipe. The solid line c in the middle portion of Fig. 4 shows tube temperatures such as observed under operating conditions when non-uniform air hole distribution as shown by curve b is employed. This represents highly satisfactory heater performance. The dot-and-dash line f is a tube temperature curve such as obtained by the uniform air hole distribution represented by curve e. It will be noted that curve f represents a very undesirable temperature distribution, since the temperature adjacent the mid-portion of the combustion tube is much higher than adjacent the fuel inlet end. Furthermore, the temperature at the end where the waste gases exit is much lower than the temperature at the fuel entrance end. As compared with this, the curve c shows substantially uniform temperatures throughout the length of the combustion tube.

In designing a new size of radiant tube heater, I first establish a tentative air hole distribution based upon an arbitrary curve similar to curve b and having such upward concavity as experience indicates to be approximately correct. Air holes are then located along the secondary air pipe as determined by a zig zag line similar

to line a, whose crests lie on or near the arbitrarily assumed curve. I usually place two or more holes at a given location, since a single hole is not likely to affect the full periphery of the combustion tube with satisfactory uniformity.

I now assemble a complete heater in a test furnace and place it in operation. Under suitable conditions of furnace temperature and fuel input, the tube surface temperature is observed, preferably with an optical instrument, at points throughout its effective length. If the distribution is found satisfactory, the tentative spacing is approved. If unsatisfactory, a corrected spacing is provided and the observation repeated. It will be readily understood that too high a temperature at a given point indicates that too much secondary air has been admitted ahead of that point, and too low a temperature indicates too little air.

In the preferred embodiment of the invention as described, a mixture of gas and air is introduced into one end of the combustion tube and the required additional amount of secondary air for completing combustion is introduced through the secondary air pipe. However, my invention may also be practiced when fuel only, rather than a rich mixture of fuel and air, is supplied at the inlet end of the combustion tube. With fuels of relatively high hydrocarbon content, including natural gas, commercial propane and butane, retort coal gas, and the like, such a method of firing leads to "cracking" of the hydrocarbons in the initial combustion zone, with deposit of solid carbon. When using such fuels, serious difficulty from accumulation of carbon can be avoided only by the use of "primary" air, usually 50% or more of the required total. However, certain producer gases whose combustible content is largely CO and H₂, are substantially free from the tendency to deposit carbon, and do not require the use of primary air. With such fuels the entire air supply may be introduced through the pipe 16, with appreciable advantage through the increased amount of waste heat recovery. The present invention is equally advantageous in this case, because the greater quantity of air introduced through the air pipe would otherwise actually increase the variation in air temperature between different locations and the blowpipe effect of the air jets.

It will be obvious that the same empirical procedure may be used for determining air hole distribution as when employing primary air.

It will be seen from the construction which has been described that the air hole distribution along the length of the secondary air pipe is not uniform but is graduated so that the secondary air is admitted to the combustion zone at a greater rate per unit of combustion zone length near the outlet than near the inlet end of the combustion zone. The secondary air outlet orifices are so proportioned as to compensate for the differences in temperature of the secondary air discharged at various points along the secondary air pipe 16. Thus, as shown in Fig. 1, the air jets issuing from the openings 11 located adjacent the right hand end of the air pipe are not heated to as high a temperature as that issuing from the openings adjacent the left hand end of the air pipe. There are only two air openings in each series at the left hand end, whereas there are four openings in each series adjacent the right hand end. The increased area of the secondary air openings adjacent the right hand

end compensates for the lower temperature of the air issuing from these openings. It will be noted further that the total area of the air holes lying to the left of the mid-portion of the secondary air pipe is less than the total area of the air hole openings lying to the right of the mid-portion.

As previously pointed out, the curve B shown at the bottom of Fig. 4 is upwardly concave. The curve is of generally constantly increasing slope from the beginning toward the end of the curve. This type of curve has been found in actual practice to produce substantially uniform temperature distribution throughout the effective length of the combustion tube under the conditions which have been referred to. In determining the area and distribution of air holes to be used in an air pipe for a radiant heater of a different size from that already constructed, the location and number or area of secondary air orifices at each location should be such as to produce a curve similar to curve b. This is done by employing a graph on which the ordinate represents the total air hole area between the face of the furnace wall adjacent the fuel inlet and the point of the air tube in question. The abscissa represents the distance between the furnace wall face just referred to and the point on the secondary air pipe where the hole or holes are to be located. The place of location and the total air hole area are then selected so that when the points are plotted on the graph they form a curve which is upwardly concave.

In the illustrated embodiment of the invention, I use a perforated air pipe. Instead of a single perforated air pipe, I may use several smaller pipes terminating in open ends at different points in the combustion zone and when an air pipe is referred to in the claims it is intended to include such construction.

Although I have illustrated and described a preferred embodiment of my invention, it is to be understood that the invention is not limited thereto but may be otherwise embodied or practised within the scope of the following claims.

I claim:

1. In a heater for furnaces and the like, an imperforate elongated outer tube having a fuel inlet end portion, an outlet end portion, and a portion enclosing a combustion zone intermediate said end portions, means for supplying fuel to the combustion zone at the inlet end thereof, and a conduit traversing said outer tube through the outlet end thereof and through the major part of the length of the combustion zone, said conduit having air discharge orifices at points within the combustion zone so disposed as to discharge air at a progressively greater rate per unit of combustion zone length near the outlet than near the inlet end of the combustion zone.

2. In a heater for furnaces and the like, an imperforate elongated outer tube having a fuel inlet end portion, an outlet end portion, and a portion enclosing a combustion zone intermediate said end portions, means for supplying a predetermined mixture of fuel and air insufficient for complete combustion to the combustion zone at the inlet end thereof, and a conduit traversing said outer tube through the outlet end thereof and through the major part of the length of the combustion zone, said conduit having air discharge orifices at points within the combustion zone so disposed as to discharge air at a progressively greater rate per unit of combustion

70 zone length near the outlet than near the inlet end of the combustion zone.

3. In a heater for furnaces and the like, an imperforate elongated outer tube having a fuel inlet end portion, an outlet end portion, and a portion enclosing a combustion zone intermediate said end portions, means for supplying fuel to the combustion zone at the inlet end thereof, and means for supplying air to the combustion zone for progressive combustion of the fuel, said means including a conduit entering through an end portion of said outer tube and traversing at least a substantial part of the length of the combustion zone, said conduit having air outlets so disposed as to discharge progressively greater amounts of air in relation to the combustion zone length near the point of air entry than remote therefrom.

4. A radiant tube heater for furnaces and the like, comprising an imperforate combustion tube, means for supplying combustible material to one end of said tube, an air pipe within said tube and provided with air holes arranged at intervals therealong for supplying air flowing in a direction countercurrent to the flow of products of combustion, the sum of the areas of the holes from the mid-portion to the air inlet end of the air pipe exceeding the sum of the areas of the holes from the mid-portion to the end of the air pipe remote from the inlet end.

5. A radiant tube heater for furnaces and the like, comprising an imperforate combustion tube, means for supplying combustible material to one end of said tube, an air pipe within said tube and provided with air holes spaced therealong, the spacing of the holes lengthwise of the pipe and the air hole area at any point along the air tube being so related that when distances measured from the inner face of the furnace wall adjacent the fuel inlet to the air hole points on the air pipe are plotted as abscissa and the total air hole area between said face and the point of the air tube in question are plotted as ordinates, the curve of the plotted points is upwardly concave.

6. A radiant tube for furnaces and the like, comprising an imperforate combustion tube, means for supplying combustible material to one end of said tube, an air pipe within said tube and provided with air holes arranged at intervals therealong, the total area of such air holes from the end of the air pipe remote from the air inlet end of the pipe to a mid-zone therein being less than the total area of air holes from the mid-zone to the inlet end of the pipe, the distribution and the area of the air holes being such that a graph plotting the sum of the areas of the air holes on its ordinate against the distance between a given point on the air pipe and the inner face of the furnace wall adjacent the fuel inlet on its abscissa is a curve of generally constantly increasing slope from the beginning toward the end of the curve.

7. A radiant tube heater for furnaces and the like, comprising a combustion tube, means for supplying combustible material to one end of said tube, an air pipe within said tube and provided with air holes spaced therealong, and baffles located adjacent the air holes for preventing direct impingement of the air on the combustion tube and for creating turbulence of the combustible material and air.

8. An air tube for an internally fired heating tube and adapted to extend through the outlet and the major portion of the combustion zone of said heating tube, said air tube having a plurality

of spaced discharge orifices within the combustion zone and means associated with said orifices for deflecting and distributing the air issuing therefrom.

9. An air tube for an internally fired heating tube and adapted to extend through the outlet and the major portion of the combustion zone of said heating tube, said air tube having a plurality of spaced discharge orifices within the combustion zone and means associated with said orifices for deflecting and distributing the air issuing therefrom, the distribution of orifices within the combustion zone being such that the orifice area per unit length increases from the inlet to the outlet end of the combustion zone.

10. In an internally fired heating tube, means for obtaining a desired temperature distribution in the heat-radiating portion of the tube, said means including an internally disposed air conduit having orifices for discharging air for combustion into the combustion space and baffles associated with said orifice for deflecting and distributing said air after discharge.

11. In an internally fired heating tube, means for obtaining a desired temperature distribution in the heat-radiating portion of the tube, said means including an internally disposed air conduit having orifices for discharging air for combustion into the combustion space and baffles associated with said orifices for deflecting and distributing said air after discharge, said orifices being so located in respect to the length of said heat-radiating portion as to compensate for the temperature of the air discharged therefrom.

12. A radiant tube heater for furnaces and the like, comprising an imperforate combustion tube, means for supplying combustible material to one end of said tube, an air pipe within said tube and provided with air holes spaced therealong, the spacing of the holes lengthwise of the pipe and the air hole area at any point along the air tube being so related that when distances measured from the inner face of the furnace wall adjacent the fuel inlet to the air hole points on the air pipe are plotted as abscissa and the total air hole area between said face and the point of the air tube in question are plotted as ordinates, the curve of the plotted points is upwardly concave, and baffles located adjacent the air holes for preventing direct impingement of the air on the combustion tube and for creating turbulence of the combustible material and air.

13. A radiant tube heater for furnaces and the like, comprising an imperforate combustion tube, means for supplying combustible material to one end of said tube, an air pipe within said tube and provided with air holes spaced therealong, a recuperator in the combustion tube for preheating air supplied to the air pipe, the spacing of the holes lengthwise of the pipe and the air hole area at any point along the air tube being so related that when distances measured from the inner face of the furnace wall adjacent the fuel inlet to the air hole points on the air pipe are plotted as abscissa and the total air hole area between said face and the point of the air tube in question are plotted as ordinates, the curve of the plotted points is upwardly concave.

14. A radiant type heater for furnaces and the like, comprising an imperforate combustion tube, means for supplying combustible material to one end of said tube and discharging products of combustion from the opposite end of said tube, an air pipe within said tube and provided with air holes arranged at intervals therealong through-

out the major portion of the combustion tube, the air hole area increasing progressively per unit of air tube length in the direction of flow of products of combustion and throughout the major portion of the combustion tube.

15. A radiant type heater for heat treating furnaces containing a controlled atmosphere for the work being treated, said heater comprising an imperforate combustion tube, having a length at least several times its diameter, means for supplying combustible material to one end of said combustion tube and discharging products of combustion from the opposite end of said tube, an air pipe within said combustion tube for supplying air flowing in a direction countercurrent to the flow of products of combustion, said air pipe provided with air holes arranged at intervals therealong throughout the major portion of the air pipe length, the air hole area increasing progressively per unit of air pipe length in the direction of flow of products of combustion.

16. A radiant type heater for heat treating furnaces containing a controlled atmosphere for the work being treated, said heater comprising an imperforate combustion tube having a length at least several times its diameter, means for supplying combustible material to one end of said combustion tube and burning said material in contact with said tube and discharging products of combustion from the opposite end of said tube, an air pipe within said combustion tube for supplying air flowing in a direction countercurrent to the flow of products of combustion, said air pipe provided with air holes arranged at intervals therealong throughout the major portion of the air pipe length, the air hole area increasing progressively per unit of air pipe length in the direction of flow of products of combustion.

17. A radiant type heater for heat treating furnaces containing a controlled atmosphere for the work being treated, said heater comprising an imperforate combustion tube having a length at least several times its diameter, said combustion tube having its external heat radiating surface freely exposed to the furnace atmosphere, means for supplying combustible material to one end of said combustion tube and discharging products of combustion from the opposite end of said tube, an air pipe within said combustion tube for supplying air flowing in a direction countercurrent to the flow of products of combustion, said air pipe provided with air holes arranged at intervals therealong throughout the major portion of the air pipe length, the air hole area increasing progressively per unit of air pipe length in the direction of flow of products of combustion.

18. A radiant type heater for heat treating furnaces containing a controlled atmosphere for the work being treated, said heater comprising an imperforate combustion tube having a length at least several times its diameter, said combustion tube having its external heat radiating surface located so as to freely supply heat to the furnace, means for supplying combustible material to one end of said combustion tube and discharging products of combustion from the opposite end of said tube, an air pipe within said combustion tube for supplying air flowing in a direction countercurrent to the flow of products of combustion, said air pipe provided with air holes arranged at intervals therealong throughout a substantial portion of the combustion tube, the air hole area increasing progressively per unit of air pipe length in the direction of flow

of products of combustion and throughout the perforated portion of said air pipe.

19. Heating means for furnaces comprising a combustion tube having inlet and outlet end portions and an imperforate heat-radiating portion enclosing a combustion zone intermediate said end portions, said heat-radiating portion having a length at least several times its diameter, means for supplying combustible material to the inlet end of said combustion zone and for discharging products of combustion through said outlet end portion, and a secondary air pipe extending through said outlet end portion into and through a substantial portion of said combustion zone, said secondary air pipe having air holes spaced therealong throughout substantially its entire length within the combustion zone, the area of said air holes per unit length of said pipe increasing constantly throughout said length in the direction of flow of products of combustion.

20. A radiant tube heater for furnaces and the

like, comprising a combustion tube, means for supplying combustible material to one end of said tube, an air pipe within said tube and provided with air holes spaced therealong, baffles located adjacent the air holes for preventing direct impingement of the air on the combustion tube and for creating turbulence of the combustible material and air, and means for spacing said baffles from the combustion tube.

21. A radiant tube heater for furnaces and the like, comprising a combustion tube, means for supplying combustible material to one end of said tube, an air pipe within said tube and provided with air holes spaced therealong, baffles located adjacent the air holes for preventing direct impingement of the air on the combustion tube and for creating turbulence of the combustible material and air, and centering lugs associated with at least one of said baffles for spacing the baffles from the combustion tube.

ARTHUR H. VAUGHAN.
